W. Randolph Jr.
Attorney

UNITED STATES PATENT OFFICE.

CLIFTON M. INGRAM, OF PORTER, OKLAHOMA, ASSIGNOR OF ONE-HALF TO ROBERT L. DEDMON, OF PORTER, OKLAHOMA.

WELL-DRILLING TOOL.

Application filed October 7, 1924. Serial No. 742,251.

To all whom it may concern:

Be it known that I, CLIFTON M. INGRAM, a citizen of the United States, residing at Porter, in the county of Wagoner and State 5 of Oklahoma, have invented certain new and useful Improvements in Well-Drilling Tools; and I do hereby declare the following to be a full, clear, and exact description of the invention, such as will enable others 10 skilled in the art to which it appertains to make and use the same.

This invention provides a tool adapted for use in drilling oil, artesian and other deep wells to prevent loss of the drilling tool and 15 abandonment of the well in the event of the drill stem becoming stuck in the well.

To this end the device consists in the provision of means for removing sand, mud, and other matter from around the drill stem 20 and head and comprises a cylindrical casting made of two similar sections hingedly secured together and each section comprising concentric walls spaced apart to form a space to receive the sand, mud, etc., and a 25 valve in the bottom of the section in each instance that will open to permit the sand and mud to enter the space between the walls and will close to hold the matter therein for removal from the boring. The space en- 30 closed by the inner walls being provided to permit the use of the tool while the drill stem is in place in the well as would be obviously necessary should the drill stem and 35 drill be stuck in the well as stated.

While the drawings illustrate an embodiment of the invention it is to be understood that in adapting the same to meet different conditions and requirements, various changes in the form, proportion and minor 40 details of construction may be resorted to without departing from the nature of the invention.

Referring to the accompanying drawings forming a part of the specification,

Figure 1 is an elevational view of one 45 form of the tool comprising similar annular sections hingedly connected and held closed by suitable fastening means, parts being broken away,

Figure 2 is a similar view taken at a right

angle to Figure 1, parts being broken away, Figure 3 is a bottom view, and Figure 4 is a sectional view taken on the line 4—4 of Figure 1.

Corresponding and like parts are referred 55 to in the following description and designated in the several views of the drawings by like reference characters.

In the preferred form of the invention, the tool appears as a double walled cylinder, 60 comprising similar sections which are hingedly connected at one side and secured at the opposite side by suitable fastening means. The annular formation of the tool comprises a space 1 between the outer and inner 65 walls 2 and 3, and this space is adapted to receive the sand, cuttings, or other material thereby preventing the binding of the drill stem which passes freely through the central opening 4 formed by the inner sectional 70 wall 3. A plurality of valves 5 close the lower end of the annular space 1 and are adapted to open upwardly and each valve 5 is provided with an extension 6 which engages the sand or other material in the well 75 to open the valves to admit of the material passing into the space 1, said valves closing downwardly when the device is elevated to relieve the projections 6 from upward pressure. An inner seat 7 limits the downward 80 closing of each of the valves. The projections 6 are of loop formation and cooperate with cross pins 8 whereby to limit the upward movement of the valves. As heretofore stated the device is in two sections 85 hingedly connected by means of hinges 2^a secured to walls 2, and 2^b indicate one or more latches to hold the two sections in cylindrical formation.

A bail is provided for operating the device 90 and because of the sectional formation of the device the bail is also of sectional formation, the sections being similar and each consisting of a lower curved portion 9 and a shank portion 10 terminating in an eye 11 to 95 receive the operating rod or cable.

What is claimed is:—

1. A device of the class described comprising two similar semi-cylindrical sections hingedly secured together and arranged to 100

be secured in cylindrical formation, each of said sections comprising two walls spaced apart, and a valve mounted in the bottom of each section to control communication with 5 the space between said walls.

2. A device of the class described comprising two similar semi-cylindrical sections each consisting of two concentric walls spaced apart, said sections being hingedly 10 secured together and adapted to be secured

in cylindrical formation, inwardly extending shoulders on said walls, and a valve seated on the shoulders in each section.

In testimony whereof I affix my signature in presence of two witnesses.

CLIFTON M. INGRAM.
